DRAWING KIT

Filed May 25, 1927

UNITED STATES PATENT OFFICE

JUSTIN R. SWIFT, OF EVANSTON, ILLINOIS, ASSIGNOR TO THE SUPERIOR TYPE COMPANY, OF CHICAGO, ILLINOIS, A CORPORATION OF ILLINOIS

DRAWING KIT

Application filed May 25, 1927. Serial No. 194,107.

My invention relates to drawing boards and particularly to an improvement on the construction shown in the copending application of William E. White, Serial Number 177,494, filed March 23, 1927.

An object of my invention is to provide a complete and compact drawing kit in which I utilize a container in the form of an elongated, rectangular, flat box, having a laterally sliding drawer adapted to contain paper and drawing instruments. Means are provided for securing the drawing paper to the upper flat side of the box, a side and end of the box cooperating with the head of a T-square in the manner of a drawing board.

The means for securing the drawing paper to the upper surface of the box without interference with the use of the T-square or triangle constitutes an important part of my invention. Such means, in order to be thoroughly practical, should be so constructed that they may be carried within the container and readily applied and removed.

Complete equipment including drawing instruments, pens, pencils, ink, paper, slide rule, etc., may be accommodated within the drawer and the drawer is held in closed position by a suitable catch. The assembly is neat, compact and ample for all ordinary drawings and sketches such as made in the field.

The invention will be more readily understood by reference to the accompanying drawing, in which;

Fig. 1 is a perspective view of an outfit such as contemplated by me;

Fig. 2 is a fragmentary sectional view on the line 2-2 of Fig. 1;

Fig. 3 is a perspective view of the closed box with a pad of paper held in proper relation on the top surface of the box;

Fig. 4 is a sectional view on the line 4-4 of Fig. 3;

Fig. 5 is a fragmentary sectional view on the line 5-5 of Fig. 4; and

Fig. 6 is a fragmentary perspective view of one of the sheet holders.

In the drawings it will be seen that the box of my invention is of rectangular form having a top wall 10, back wall, 11, bottom wall

12 and end wall, 13. The side opposite the wall 11 is open to receive a drawer 14 having suitable partitions, 15, therein. Secured to the bottom and end walls of the drawer and within the same is a small box, 16, containing a coil spring 17, and a plunger 18, actuated by the spring. The plunger extends through the end wall of the drawer and is adapted to enter a suitable opening in the end wall 13 of the box to act as a catch for the drawer. This is located, as shown, at a point inwardly of the outer edge of the drawer. A finger hole, 19, in the rear wall 11 of the box is located near one end of the box so that the pressure exerted on the drawer through the finger hole will be properly directed to displace the drawer when the plunger 18 is compressed.

The top wall 10 of the box is provided with a plurality of elongated slits 20 located near the side margin thereof. These slits cooperate in the performance of two functions. They are shaped to receive downturned ears 21, formed at the side edge of a metal pad back, 22, upon which may be mounted a pad 23 of paper, indicated at 23. As a means for holding the pad on the pad back, I provide downturned margins 24 at the two sides of the pad back and within these downwardly and inwardly turned margins the board back 25 of the pad is held. When the pad is then reversed or swung backwardly to the top of the pad back and the pad back located as shown in Fig. 3, the parts are in position for use with a T square and triangle if desired. The depth of the head of the triangle is such that it will cooperate with the side wall of the box notwithstanding the thickness of the pad.

If, however, a single sheet of paper is to be used instead of the entire pad, I utilize the slits in cooperation with the bowed sheet holders 26. These sheet holders as best shown in Figs. 1, 2 and 6 are in the form of flat resilient, bowed, strips of metal both ends of the strip being angularly bent. The bent end, 27, is rebent as at 28, to cooperate with the slit in the box, as best shown in Fig. 2. The end 29 is merely bent into somewhat of a hook, in order that it may engage with the edge of the top wall of the box. Due to the

elongated slits, the sheet holders may be positioned as desired in order to hold sheets of different sizes. The holders do not interfere with the use of the T square as indicated in Fig. 1, nor with the closing of the drawer. Preferably a fibre or other board, 30 will be placed beneath a sheet held in the manner described in order to enable the use of pointed drawing instruments, such as compasses etc.

10 It will be noted that the partitions 15 on the box are of less height than the sides of the box thereby permitting the pad and pad back to be placed within the drawer. In fact, all the illustrated parts including the T-square, 15 sheet holders, pad etc., are constructed to be received within the drawer. When so received and the drawer closed, the kit is compact and complete and may be carried easily in a hand bag or in the hand.

20 Obviously the construction is capable of some modification, and I do not wish to be limited except as indicated in the appended claims.

I claim:

25 1. In combination, a box, the top wall thereof having an aperture near one edge, and a normally bowed, resilient member having hook ends, one of said hook ends including an off-set part adapted to engage with the 30 underside of said top wall adjacent the aperture, and the other hook end of said member being adapted to engage another portion of the box to removably connect the member to the box.

35 2. In combination, a box, the top wall thereof having an aperture near one margin, and a bowed spring retainer having hook ends, one of said hook ends including an off-set part to engage the underside of said top wall 40 adjacent the aperture, and the other hook end of said retainer being adapted to engage with the opposite margin of the box to removably connect the retainer to the box.

In testimony whereof I have affixed my 45 signature.

JUSTIN R. SWIFT.
